UNITED STATES PATENT OFFICE.

TRACY D. MONTEE, OF ILOILO, PHILIPPINE ISLANDS.

PRESSURE-OPERATED SWITCH.

1,416,491.

Specification of Letters Patent. Patented May 16, 1922.

Application filed October 18, 1920. Serial No. 417,671.

To all whom it may concern:

Be it known that I, TRACY D. MONTEE, a citizen of the United States, residing at Iloilo, Philippine Islands, have invented certain new and useful Improvements in a Pressure-Operated Switch, of which the following is a specification.

This invention relates to devices for automatically cutting out the source of power for engines of various kinds when the lubricating element runs low, and has for one of its objects to simplify and improve the construction and increase the efficiency and utility of devices of this character.

Another object of the invention is to provide a device of this character having means whereby the parts operated by the pressure of the liquid in the cylinder, may be locked in inoperative position.

With these and other objects in view, the invention consists in certain novel features of construction as hereinafter shown and described and then specifically pointed out in the claims, and in the drawings illustrative 25 of the preferred embodiment of the invention:

Figure 1 is a side elevation.

Fig. 2 is a plan view.

Fig. 3 is a vertical section on the line 30 3—3 of Fig. 1.

The improved device comprises a cylinder 10 having a bracket 11 whereby it may be attached to a suitable support. Attached to one end of the cylinder is a closure 12 into which a coupling member 13 is connected for a supply of liquid under pressure. The improved device is designed more particularly for connection with an oil pump whereby an engine is supplied with a lubricant, and the 35 coupling 13 is adapted to be connected to such a device, not shown, as it forms no part of the present invention. The closure 12 is provided with a suitable packing element 14, and is held in position by clamp screws 15.

Disposed within the cylinder 10 is a relatively long plunger 16 against whose lower end the liquid passing through the intake 13 exerts its force to maintain the plunger normally in elevated position.

At the end opposite to the closure 12 the cylinder 10 is enlarged slightly as shown at 17, and the plunger extends by a reduced portion 18 into the chamber produced by the enlargement, as shown and leading from the 55 enlarged portion of the cylinder, is an air escape or vent device 19.

Extending from the reduced portion 18 of the plunger 16 and through the adjacent end of the cylinder, is a stem 20. Attached in any suitable manner to the enlarged end of the cylinder is a supporting plate 22 preferably with upturned edges 23, and bearing upon this plate and between the upturned edges is another plate 24 of insulating material such as fibre, rubber, or the like, and secured in position by clamp screws or like devices 21.

Attached to the fibre member 24 and extending in advance of the supporting member 22, is a relatively long contact 26, the free end of the contact terminating relatively near the stem 20. The contact 26 is preferably of resilient material with its free end normally spaced from the insulated plate 22.

The fastening screw 25 is adapted to connect a suitable electric conductor, a portion of which is represented at 27, adapted to be connected to a suitable controlling or governing device, such as a magneto, not shown.

Attached to the outer end of the stem 20 is a disk 28 which extends over the free spaced end of the contact 26, and is adapted to contact therewith when the plunger is moved in the cylinder.

Pivoted at 29 in ears 30 rising from the member 22, is a weighted stop lever 31 adapted to extend by its shorter end into the path of the disk 28. The shorter end of the lever 31 is sufficiently thick to hold the disk 28 from contact with the member 26, when disposed in horizontal position, as shown in Fig. 1, and thus lock the device from operation or from functioning, as hereafter explained.

The device as shown, being associated with the oil pump of an engine, the pressure created by the pump will cause a portion of the oil to pass into the cylinder beneath the plunger which it will elevate and hold in elevated position so long as the pressure continues. The plunger being thus elevated will hold the disk 28 from contact with the member 26. The weighted end of the lever 31 will also hold the shorter end thereof out of the path of the disk 28.

If the flow of oil ceases from any cause, the pressure against the plunger will also cease the latter will fall by gravity carrying the disk 28 with it which will contact with the member 26 and short circuit the magneto or other controlling element with which the

member 27 is coupled, and thus stop the engine until the engineer or chauffeur can supply the requisite lubricating element to the pump.

5 Thus it will be impossible for the engine to run "dry".

When starting the engine it is necessary to raise the disk 28 and turn the lever 31 into a horizontal position or with its shorter end 10 between the disk 28 and the insulating member 24. The shorter end of the lever 31 being thicker than the contact plate 26 does not allow the disk 28 to touch the plate. As soon as the engine starts and there is pressure in the oil pipes, the disk 28 is raised to 15 its upper position. This releases the lever 31, which is heavier on the outer end, and it will drop to a perpendicular position, allowing the disk 28 to come in contact with 20 the contact plate 22 when the oil pressure ceases in the oil pipes and again short circuits the magneto.

The preferred embodiment of the invention is disclosed in the drawings and set 25 forth in the specification, but it will be understood that any modifications within the scope of the claims may be made in the construction without departing from the principle of the invention or sacrificing any of its 30 advantages.

What is claimed is:

1. A device of the class described comprising a cylinder having a plunger and an inlet at one end to provide for the entrance

of liquid under pressure to maintain the 35 plunger normally at one end of the cylinder, a stationary contact device attached to the cylinder and adapted for connection with electric governing devices, a contact associated with the plunger and movable there- 40 with and held normally from contact with the stationary contact by the plunger and adapted to close a circuit when the pressure against the plunger is reduced, a stop lever pivoted near one end and having its shorter 45 end extending into the path of the movable contact whereby closing of the circuit is prevented.

2. A device of the class described comprising a cylinder having a plunger and an inlet 50 at one end to provide for the entrance of liquid under pressure to maintain the plunger normally at one end of the cylinder, a stem extending in advance of the cylinder, a stationary contact device attached to the 55 cylinder and adapted for connection with electric governing devices, a contact device attached to said stem and held normally out of engagement with the stationary contact by the plunger, and a stop lever pivoted 60 near one end and extending by its shorter end into the path of the movable contact carried by the stem whereby the closing of the circuit is prevented.

In testimony whereof, I affix my signature 65 hereto.

TRACY D. MONTEE.
